UNITED STATES PATENT OFFICE.

FREDERICK GEORGE WALKER, OF CLEVELAND, OHIO, ASSIGNOR OF ONE-HALF TO KENNETH REEVE TAYLOR, OF CLEVELAND, OHIO.

MEANS FOR MOVABLY CONTACTING ELECTRICAL CONDUCTORS.

SPECIFICATION forming part of Letters Patent No. 761,928, dated June 7, 1904.

Application filed August 12, 1903. Serial No. 169,192. (No model.)

To all whom it may concern:

Be it known that I, FREDERICK GEORGE WALKER, a citizen of the United States, and a resident of Cleveland, county of Cuyahoga, 5 and State of Ohio, have invented a new and useful Improvement in Means for Movably Contacting Electrical Conductors, of which the following is a specification, the principle of the invention being herein explained and the 10 best mode in which I have contemplated applying that principle, so as to distinguish it from other inventions.

My invention relates to devices for movably contacting electrical conductors, and is particularly adapted for use in electrically-operated traction-cars for use as what is commonly 15 known as the "trolley-wheel."

The object of said invention is to provide means of such described character which will 20 combine economy of construction and operation with efficiency; and said invention consists of means hereinafter fully described, and particularly set forth in the claim.

The annexed drawings and the following description set forth in detail certain mechanism embodying the invention, such disclosed 25 means constituting but one of various mechanical forms in which the principle of the invention may be used.

In said annexed drawings, Figure 1 represents a side elevation of the end of a trolley-pole and a device embodying my invention applied thereto, a section of a trolley-wire being also shown in connection therewith. Fig. 2 30 represents a front elevation of such above-mentioned pole and device, showing a portion thereof in axial section.

Upon the upper extremity of the trolley-pole A is provided a fork a, suitably secured, 35 in which latter is journaled, by means of a pin a', an oscillatory bracket B. This bracket is held normally in an upright position by means of a helical retractile spring b, whose retractile effect is limited by the contact of the 40 bracket with the fork a, as will be readily understood. The upper portion of the bracket B is formed with two lateral inclined surfaces b b', Fig. 2, upon each of which is seated a trolley-wheel C. These wheels are each jour- 45

naled upon a journal-pin c c, which is secured 50 by means of a nut c' c', each pin being provided with a suitable head c² c². The journal-bearing of each wheel is formed by a lignum-vitæ or white-metal bushing c³, intermediate of which and the wheel is placed a ring c⁴, of 55 insulating material. A similar insulating-ring c⁵ is placed between the pin and the contiguous portion of the bracket, as shown. Intermediate of each wheel and the opposing face of the bracket and between it and the pin-head are placed insulating-washers c⁶ c⁷, respectively, so that it will be seen that the said pins and bushings are completely insulated 60 from the bracket and also from the wheels. Between each wheel and the opposing bracket- 65 face is placed a spring D, of conducting material, which bears against its respective wheel and forms electrical contact therewith. These springs are secured to the bracket, so as to 70 form electrical connection therewith, whereby current may be conducted through the trolley-pole. As shown, the axes of the pins c c are perpendicular to the bracket bearing-surfaces, lie in a common and transverse plane, Fig. 1, and are hence inclined relatively to each other. The wheels are made 75 of equal diameter, and each has a grooved periphery, as shown, the inner groove-flange of each being cut away, as shown, to form two beveled surfaces c⁸ c⁹, which are parallel 80 with each other at their points of nearest approach to each other, as shown in Fig. 2. At the upper plane in which such point (its nearest approach) occurs the two grooves form a contact-pocket c⁰ for the reception of 85 the trolley-wire, one half of same being formed by one wheel and the other half by the other wheel. It will hence be seen that a trolley-wire may be caused to contact said wheels simultaneously, as shown in Fig. 2, permitting 90 both wheels to rotate as is required, such simultaneous contact taking place when the trolley-wire is in the plane of the trolley-pole. When such is, however, not the case, as when the car is passing around a curve in the track, the 95 wire is caused to contact but one of the wheels, as shown in the dotted lines. In so contacting but one wheel it will be seen that the wire

assumes a position in which its axis lies at the point of contact substantially in the central plane of the wheel, so that the rounding of curves is accompanied by a perfect rotation 5 of the wheel, and hence an absence of slip-page between wheel and trolley-wire and a very material reduction in the liability of a separation thereof and the consequent breaking of contact, which is so frequently experienced in the operation of this class of devices.

I have found that by insulating the journal-pins completely, so as to prevent the passage of current therethrough, a greater life of the 15 bearings, and consequently of the wheels, is secured, particularly where soft-metal bushings are used, as compared with the construction in which the current is received and conducted thereby.

20 In the construction shown in the drawings the trolley-wire is illustrated as being at a maximum height.

Other modes of applying the principle of my invention may be employed instead of the 25 one explained, change being made as regards

the mechanism herein disclosed, provided the means stated by the following claim or the equivalent of such stated means be employed.

I therefore particularly point out and distinctly claim as my invention—

30 In means for movably contacting electrical conductors, the combination of a main support, a secondary support pivoted upon such main support, a retractile spring attached to such two supports respectively, said secondary support comprising two laterally-inclined surfaces to each of which is secured a journal-pin, grooved trolley-wheels mounted upon said pins and arranged to have their peripheries together to form a pocket for the 35 reception of a trolley-wire, bushings within said wheels forming bearings for said pins, and electrically insulated from said wheels and said secondary support, said wheels being electrically insulated from said pins.

40 Signed by me this 29th day of July, 1903.

45 FREDERICK GEORGE WALKER.

Attest:

D. T. DAVIES,
A. E. MERKEL.
